UNITED STATES PATENT OFFICE.

JEROME B. BELL, OF WILMINGTON, DELAWARE, ASSIGNOR TO MERGENTHALER LINOTYPE COMPANY, OF NEW YORK, N. Y., A CORPORATION OF NEW YORK.

LINOTYPE-MATRIX.

1,115,274.

Specification of Letters Patent. Patented Oct. 27, 1914.

Application filed May 6, 1911. Serial No. 625,549.

To all whom it may concern:

Be it known that I, JEROME B. BELL, a citizen of the United States, and resident of Wilmington, in the county of New Castle, State of Delaware, have invented certain new and useful Improvements in Linotype-Matrices, of which the following is a specification.

This invention relates to an improvement in linotype machines and particularly in matrices for such machines and the means for storing such matrices in magazines whereby they may be readily available for composition.

The widths of letters which may be cast in linotype machines, as heretofore used, have been limited by the widths of the matrices which the machines have been adapted to use and the widths of the matrices have been limited by the magazines, which cannot be constructed of great width without danger of transposition of the matrices during assemblage.

According to the present invention I may cast letters any width desired in machines as at present constructed and I accomplish this by putting different longitudinal zones or sections of the letters on adjacent matrices, whereby when the matrices are assembled complete letters are presented to the mold.

The invention will be more clearly understood by reference to the accompanying drawing, in which:

Figure 1 is an edge view of two matrices carrying a single letter, each matrix carrying one-half of the letter; Fig. 2 is a side view of one of these matrices; Fig. 3 is a diagrammatic view of a matrix channel in which matrices similar to those shown in Fig. 1 are assembled; Fig. 4 is a view similar to Fig. 1, but showing a wider letter extending over three matrices; and Fig. 5 is a view of an assembled line of matrices embodying the invention. Fig. 6 is a diagrammatic view illustrating the assembling and distributing mechanism of a linotype machine.

Referring to the drawing, m' , m'' indicate two matrices containing, respectively, complementary parts of a letter which is too wide to be carried by a single matrix, for reasons hereinbefore stated. The matrices may be otherwise of any ordinary form

adapted for a line or letter casting machine. As shown in the various views of the drawings my invention is adapted to the matrices now commonly used in the well known linotype machines, such matrices having upper lugs 1, lower lugs 2, and combinations of teeth in V-shaped notches 3 for cooperating with a distributing rail.

As shown in Fig. 1 the left portion of the matrix of the letter B is engraved or stamped on the left matrix m' , while the right portion of the same letter is engraved or stamped on the succeeding matrix m'' . These complementary portions of the letter B register with each other when the matrices are assembled for casting and a single wide letter may be cast against them. Any other letter or character which is wider than a single matrix may be thus formed on a plurality of matrices.

A magazine having separate channels for the different matrices of a font constructed according to my invention would be too wide for use in a linotype machine, as it would have to be about twice as wide as an ordinary magazine. To obviate this difficulty and to permit of the use of my invention in connection with linotype machines as now constructed I arrange the matrices for any given letter in a single channel, as shown in Fig. 3. Referring to this figure it will be seen that a matrix m' is at the bottom of the channel and that matrices m' , m'' are arranged alternately in the channel, the uppermost matrix being the same as the lowest matrix. In assembling these matrices the key for letter B is operated twice in succession, the first time releasing the matrix m' and the second time releasing the matrix m'' , which matrices drop into the assembler and are assembled as shown in Fig. 1.

In a linotype machine the matrices are distributed in the reverse of the order in which they are assembled and the right matrix m'' will therefore drop into the channel C ahead of the left matrix m' of any pair. In order that the matrices may always be in proper order in the channel I load each channel with one odd matrix for casting the left side of the character which the channel contains. Thus in Fig. 3 the lowest matrix and the uppermost matrix are the same and when a pair of matrices,

as shown in Fig. 1, are distributed into the channel the right matrix m^2 will follow the uppermost matrix m^1 . A pair of matrices arranged in proper order will therefore always be found at the bottom of each channel and ready for conjoint use. I have not shown any distributing or assembling mechanism in the drawing as it will be readily understood that these mechanisms 5 may be exactly the same as in the present commercial linotype machine. A suitable assembling and distributing mechanism is shown for instance in the Mergenthaler Patent No. 436,532.

15 It will be evident that my invention may be extended to wider letters than that illustrated in Fig. 1, by extending the letters over three or more matrices. In Fig. 4 I have shown a cap letter E extending over 20 three matrices m^3 , m^4 , m^5 . When using more than two matrices for a single letter the scheme of arranging them in the magazine channel shown in Fig. 3 must be modified. When a letter requires three matrices, 25 as shown in Fig. 4, the left matrix m^3 and the middle matrix m^4 may be distributed into the same channel in the manner heretofore described, one extra matrix m^5 being used. The right matrix m^5 may be distributed 30 into a separate channel, which may be the channel for the corresponding small cap letter. It is not necessary that the matrices for any single letter should all be of the same width. On the other hand it is sometimes advisable or necessary to make them 35 of different widths. For instance, in the group of matrices shown in Fig. 4 the matrix m^5 may be of the proper width to fit the channel in which it is contained and 40 the matrices m^3 , m^4 may be of another width suitable for the channel in which they are contained. It is only necessary that the aggregate width of the group of matrices should be sufficient to accommodate the desired letter. In practice matrices of various 45 widths will be used, as illustrated in Fig. 5.

Fig. 6 illustrates the distributing and assembling mechanism of one form of typographic machine in which my improved 50 matrices may be used, viz: the well known Mergenthaler linotype machine. Referring to this figure, A indicates the distributing screws; B, the magazine; C, the assembling belt; D, the key-board; and E, the mold 55 wheel. The matrices in the magazine B are liberated by operating the key-board and are carried by the belt C and assembled at the point F. The assembled line of matrices follows the direction indicated by the arrows 60 to the casting location G and from this point they follow the arrows to the distributing screws A, by means of which and associated devices the matrices are returned to their respective channels in the magazine B.

65 Having thus described my invention what

I claim and desire to secure by Letters Patent is:

1. A plurality of linotype matrices provided respectively with complementary portions of the same letter or character adapted to be assembled together to produce the complete letter or character and having the same distributing combinations, whereby they are directed to the same magazine channel. 70
2. The combination with a magazine channel of matrices bearing complementary parts of the same letter or character adapted to be assembled together to produce the complete letter or character and arranged in said channel in the order of composition. 75
3. The combination with a magazine channel of matrices bearing laterally complementary halves of the same letter or character arranged alternately therein. 80
4. The combination with a magazine channel of matrices bearing complementary halves of the same letter or character arranged alternately therein, said channel containing an even number of matrices bearing one-half of the character and an odd number of matrices bearing the other half of the character, for the purpose set forth. 85
5. A font of linotype matrices embodying a series of groups of matrices provided with distributing means, each group comprising laterally complementary vertical zones of a single character adapted when assembled to present a complete matrix of the character for casting purposes and having the same distributing combinations whereby they are 90 distributed into a common channel. 95
6. In a typographical machine, the combination of a plurality of laterally-complementary type or matrices, each containing a portion of the extended character, and adapted to be assembled side by side, and a single selecting means therefor, the successive operation of which delivers the individual type or matrices in proper consecutive order. 100
7. In a typographical machine, the combination of a plurality of laterally-complementary type or matrices, each containing a portion of the extended character, and adapted to be assembled side by side, and a single storing means therefor, whereby the individual type or matrices are stored together in proper consecutive order. 110
8. In a typographical machine, the combination of a plurality of laterally-complementary type or matrices, each containing a portion of the extended character, and adapted to be assembled side by side, the said type or matrices being all provided with the same distributing combination, and distributing devices, whereby the individual type or matrices are all released at the same point. 120
9. In a typographical machine, the combination of a plurality of laterally-complementary type or matrices, each containing 125

a portion of the extended character, and adapted to be assembled side by side, a single storing means therefor, and distributing devices to deliver all the individual type or matrices to the single storing means in proper consecutive order.

10. In a typographical machine, the combination of a plurality of laterally-complementary type or matrices, each containing a portion of the extended character, and adapted to be assembled side by side, a single storing means for storing the individual type or matrices in proper order, a single selecting means to deliver the type or matrices successively therefrom, and distributing devices to restore the type or matrices to the storing means in the proper order.

11. In a typographical machine, a plurality of laterally-complementary type or matrices, each containing a portion of the extended character, the similar individual type or matrices being stored alternately and in

different number, in combination with selecting means for successively delivering the type or matrices in one order, and distributing means for restoring them in a different order.

12. In a typographical machine, a plurality of double, laterally-complementary type or matrices, each containing a portion of the extended character, the similar individual type or matrices being stored alternately and in odd and even number respectively, in combination with selecting means for successively delivering the type or matrices in one order, and distributing means for restoring them in the reverse order.

In testimony whereof I affix my signature in presence of two witnesses.

JEROME B. BELL.
